UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 22,927, dated November 28, 1893.

Application filed October 14, 1893. Serial No. 488,176. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification.

The design consists of a series of Rococo style of ornaments filled with sprays of flowers and leaves as represented in the accompanying drawing.

The border or upper portion of the design is formed of Rococo ornaments and scrolls forming panels with groups of flowers and leaves in the center of said panels as shown 15 in the drawing.

What I claim is—

1. The design for wall paper herein shown and described.
2. In the design for wall paper, the border 20 herein shown and described.

Witness my hand this 5th day of October, 1893.

CHARLES BOOZE.
